TOOL HANDLE FOR SPADES OR THE LIKE

Donald T. Walsh, Hindley, near Wigan, and Frank Darbyshire, Standish, near Wigan, England, assignors to English Tools Limited, Wigan, England, a company of Great Britain

Filed Sept. 8, 1959, Ser. No. 57,454

Term of patent 14 years

(Cl. D39—1)

-FIG. 1-

-FIG. 2-

Fig. 1 is a top perspective view taken from one end of a tool handle for spades or the like embodying our new design;

Fig. 2 is a bottom perspective view taken from the opposite end thereof;

Fig. 3 is an enlarged front elevational view thereof;

Fig. 4 is an end elevational view thereof; as shown in Fig. 3;

Fig. 5 is a vertical cross-sectional view thereof, taken on line 5—5 of Fig. 4; and

Fig. 6 is a transverse cross-sectional view thereof, taken on line 6—6 of Fig. 4.

We claim:

The ornamental design for a tool handle for spades or the like, substantially as shown.
